Attorney

UNITED STATES PATENT OFFICE

PAUL S. DILLON, OF FLORENCE, COLORADO, ASSIGNOR OF ONE-HALF TO CHARLES M. SMITH, OF FLORENCE, COLORADO, AND ONE-HALF TO NELLIE M. DILLON

COMBINATION COAT AND PANTS HANGER

Application filed November 13, 1930. Serial No. 495,510.

The present invention relates to a combination coat and pants hanger and aims to provide a structure which is simple, easy to manipulate, thoroughly efficient and reliable 5 in use, inexpensive to manufacture and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

15 Figure 1 is an elevation of the combination coat and pants hanger embodying the features of my invention.

Figure 2 is a perspective view of the pants engaging element.

20 Referring to the drawings in detail it will be seen that the coat hanger is formed in the present instance from a single strand of wire or the like to provide a straight cross rod 5 merging at its ends into downwardly directed loops 6 which merge into upstanding ends

25 7 which in turn merges to upwardly converging shoulder extensions 8 one of which terminates in a hook 9 and the other of which terminates in a coil 10 about the shank of the hook 9. Numerals 11 denote springs having ends engaged in the loops 6. Pants engaging elements are denoted generally by the letter P. Each element P comprises a pair of substantially spaced parallel coextensive V-shaped sides including longer legs 12

30 and shorter legs 14. The shorter legs 14 merge into the ends of a convolute 15. The springs 11 are engaged with the convolute 15.

35 The inner sides of the legs 12 are serrated 40 as indicated at 16. The legs 12 are adapted to extend into the ends of the pants legs as is indicated to advantage by the dotted line showing in Figure 1 and the springs are under tension so that the pants will be supported 45 in a hanging position to tend to maintain the creases in the legs.

It is thought that the construction, utility and advantages of the invention will now be quite apparent to those skilled in this art 50 without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction and in the combination and arrangement of parts may be resorted to without departing from the spirit or scope of the invention as hereinafter claimed or sacrificing any of its advantages.

Having thus described my invention, what I claim as new is:

1. In combination, a coat hanger having depending loop extensions at the ends thereof, springs engaged with the extensions and pants leg engaging elements on the springs, each element comprising a pair of spaced parallel coextensive V-shaped side members connected together by a convolute, the convolutes of the elements being engaged with the springs.

2. In combination, a coat hanger having depending loop extensions at the ends thereof, springs engaged with the extensions and pants leg engaging elements on the springs, each element comprising a pair of spaced parallel coextensive V-shaped side members connected together by a convolute, the convolutes of the elements being engaged with the springs and the free limbs of said side members being serrated on their inner edges to engage the garment.

In testimony whereof I affix my signature.

PAUL S. DILLON.
